US00D627064S

(12) **United States Design Patent**
Appelbaum et al.

(10) **Patent No.:** US D627,064 S
(45) **Date of Patent:** ** Nov. 9, 2010

(54) **PROBE**

(75) Inventors: **Henry R. Appelbaum**, Chicago, IL (US); **Kambiz Dowlatshahi**, Chicago, IL (US); **William Graveman**, Tonganoxie, KS (US); **Anthony J. Tomassello**, Libertyville, IL (US)

(73) Assignee: **Novian Health, Inc.**, Chicago, IL (US)

(**) Term: **14 Years**

(21) Appl. No.: **29/298,911**

(22) Filed: **Dec. 14, 2007**

(51) **LOC (9) Cl.** 24-02

(52) **U.S. Cl.** D24/130

(58) **Field of Classification Search** D24/127-130; 606/4-6; 128/898-899
See application file for complete search history.

CLAIM

The ornamental design for a probe, as shown and described.

DESCRIPTION

FIG. 1 illustrates a perspective view of a first embodiment of our new design;

FIG. 2 illustrates a right side view of the probe of FIG. 1, the left side being a mirror image thereof;

FIG. 3 illustrates a top view of the probe of FIG. 1;

FIG. 4 illustrates a first end view of the probe of FIG. 1;

FIG. 5 illustrates a second end view of the probe of FIG. 1;

FIG. 6 illustrates a perspective view of a second embodiment of our new design;

FIG. 7 illustrates a right side view of the probe of FIG. 6, the left side being a mirror image thereof;

FIG. 8 illustrates a top view of the probe of FIG. 6;

FIG. 9 illustrates a first end view of the probe of FIG. 6; and,

FIG. 10 illustrates a second end view of the probe of FIG. 6.

The broken line showing is included for the purpose of illustrating portions of the article that form no part of the claimed design.

1 Claim, 4 Drawing Sheets
